UNITED STATES PATENT OFFICE.

JOHN J. ENDRES, OF NEW YORK, N. Y.

CABLE-CAR GRIP.

SPECIFICATION forming part of Letters Patent No. 349,486, dated September 21, 1886.

Application filed January 25, 1886. Serial No. 189,600. (No model.)

To all whom it may concern:

Be it known that I, JOHN J. ENDRES, of the city, county, and State of New York, have invented certain new and useful Improvements 5 in Grips for Cable-Road Cars, of which the following is a full, clear, and exact description, and will enable those skilled in the art to which they belong to make and use the same.

The object of the present invention is the 10 production of a grip for cable-road cars that shall have advantages of simple and compact structure, easy and effective operation, and be less wearing upon the cable than the common form of grips; and the invention consists of 15 two gripping-jaws which are arranged side by side and have long gripping-surfaces, and are moved to and from each other by separate toggle mechanisms arranged at their ends and connected together so as to be simultaneously 20 operated.

In the drawings accompanying this description, Figure 1 is a plan view of a gripping mechanism embodying my invention. Fig. 2 is an elevation or side view of the same. Fig. 25 3 is a plan or top view of one of the jaws of the grip. Fig. 4 is an end view of the gripping mechanism in the position it occupies when grasping the cable; and Figs. 5, 6, and 7 are detail views of a toggle-arm and one of 30 the toggles.

Referring to these views in detail, A A are the cross-beams or other part of a car-truck to which the gripping mechanism is attached.

B is the body or frame part of the mechanism—that is, the part directly connected to the 35 cross-beams A A, and upon which the jaws move.

C are beveled ways on the under side of the body B, and upon which slide the gripping-jaws D.

E are lugs on the body B, to which are pivoted the toggle-arms F by bolts G.

H represents the toggles, they being curved, as shown, so as to work compactly around

each other and the ends of the toggle-arms, 45 and being bolted at I to the toggle-arms and at J to the ends of the gripping-jaws D.

K is a rod connecting the outer ends of the toggle-arms, and extending to any place on the car from which it may be desired to operate 50 the grip. It will now be plain that upon causing the toggle-arms to be swung one way the gripping-jaws will be moved from each other, and upon swinging these arms in the other direction the jaws will be moved toward each 55 other and caused to grip the cable if between them. The cable may be lifted, so as to be caught by the jaws, in any suitable way.

By these means I provide a gripping mechanism of great strength and very compact form, 60 and the extended gripping-surfaces of the jaws not only give it greater holding-power than is the case with the common forms of grips, but also reduce the wear upon the cable by having a long and lighter grasp, instead of, as 65 heretofore, a short and powerful grasp that caused the cable to be indented and pimpled.

What is claimed as new is—

1. In combination in a cable-car grip, two movable gripping-jaws arranged side by side 70 and independent mechanisms arranged one at each end of the jaws for moving said jaws to and from each other, substantially as set forth.

2. In combination in a cable-car grip, two movable gripping-jaws arranged side by side 75 and independent toggle mechanisms arranged one at each end of the jaws for moving said jaws to and from each other, substantially as set forth.

3. In combination, the body B, having ways 80 C, the jaws D, the toggle-arms F, and the toggles H, all arranged substantially as and for the purpose set forth.

JOHN J. ENDRES.
